CLAIM

The ornamental design for a corner shower caddy as shown and described.

DESCRIPTION

FIG. 1 is a front perspective view of a corner shower caddy showing our new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the corner shower caddy that form no part of the claimed design. The dash-dot-dot broken lines represent a symbolic breaks in the claimed design. The appearance of any portion of the article between the break lines forms no part of the claimed design. None of the broken lines form any part of the claimed design.

1 Claim, 8 Drawing Sheets
